T. B. Atterbury

UNITED STATES PATENT OFFICE.

THOMAS B. ATTERBURY, OF PITTSBURG, PENNSYLVANIA.

MANUFACTURE OF GLASS SIGNS.

SPECIFICATION forming part of Letters Patent No. 268,849, dated December 12, 1882.

Application filed November 9, 1882. (No model.)

To all whom it may concern:

Be it known that I, THOMAS B. ATTERBURY, a citizen of the United States, residing at Pittsburgh, in the county of Allegheny and State of Pennsylvania, have invented certain new and useful Improvements in the Manufacture of Glass Signs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to the manufacture of glass signs or advertising-tablets and in the ornamentation of the same.

Referring to the accompanying drawings, Figure 1 is a front view of the sign. Fig. 2 is 20 a sectional view on the line $x-x$ of Fig. 1. Fig. 3 is a sectional view, showing two of the tablets joined together to form a sign.

In an application filed by me October 14, 1882, Serial No. 74,260, for glass molds and the 25 manufacture of glass signs, I have shown molds for the manufacture of signs and advertising-tablets, in which the letters, figures, or designs are made in depression or in relief, or separate letters of metal or other material embedded therein. In this invention I 30 form the glass tablet in molds having a cavity or cavities therein of the required or desired design, the plunger being provided with a like design in relief, so that the article produced 35 will be of a uniform thickness throughout and will be more readily annealed, thus rendering the article less liable to "fly" or crack, as would be the case if made of varying thicknesses.

In the drawings I have shown a tablet, A, 40 of glass, having formed therein in relief the counterpart or representation of a snuff bottle or jar, B, in which a particular brand of snuff is put up and sold by a particular person or firm, and have chosen for the sake of illustration "Weyman Snuff."

A representation of the article which it is 45 designed to be advertised having been impressed on or in the glass tablet, if the tablet is made from clear glass, I take the trade-label 50 "a," whether printed or painted, and paste or

otherwise place it on the inside of the tablet and in the desired or proper position on the imitation bottle. I then paint the bottle or other design on the inside and over the label in any suitable or desired color, and paint the 55 balance of the tablet of any other color; or I may leave the body or border surrounding the bottle or other design of plain glass. The effect of this process is that the display of the article or design is very perfect and causes it 60 to stand out in a conspicuous and attractive manner. When I make the tablet of opaque glass the label is placed on the outside, leaving the bottle or other design in the regular color of the glass. The other portion or frame 65 of the tablet is painted of a different color; or I may paint the bottle or design portion of the tablet and leave the frame or border the natural color. Any of the changes and interchanges of colors which may suggest themselves to one skilled in this art will come within the scope of my invention. These single 70 tablets are designed for display in show-windows and in the inside of stores, where they are to show from one side only.

In Fig. 3 I have shown two tablets joined 75 together. This form of sign is designed for street display, as where it is desired to display both sides of the sign over the sidewalk or in front of the shop or store. The two sections 80 C and D composing this double sign may be joined together permanently by any suitable cement, or detachably joined by metallic or other bands or clips. This double form of sign can also be used to advantage as a transparent 85 advertising-sign, having gas or other light placed within it, provision being made by means of air or vent holes to prevent the heat from the gas or other light from breaking the sign; but when used as a transparency opal or 90 clear glass with transparent paint should be used in the manufacture of such signs.

It is obvious that almost any trade-mark can be produced in this manner, giving representation or fac-simile of the original package and 95 label in a cheap and durable manner.

Having thus described my invention, what I claim, and desire to secure by Letters Patent, is—

1. The process herein described of making 100

glass signs or advertising-tablets, the same consisting in pressing or blowing the article with the proper design therein, pasting on the design or article to be represented the appropriate trade-label, then painting the design in one color and the other portions of the tablet another color, substantially in the manner set forth.

2. A sign or tablet for advertising purposes, made of one piece of glass, having impressed thereon an imitation of the package or article to be advertised, said imitation article having the trade-label secured thereon, as set forth.

3. A sign for advertising purposes, composed of two tablets of glass having the desired designs thereon, said tablets being secured together, so as to present a single sign with both sides to the observer, as set forth. 15

In testimony whereof I affix my signature in presence of two witnesses.

THOS. B. ATTERBURY.
